Primary Examiner — Richard Kearney

Assistant Examiner — Anthony Vincent Rotolo

CLAIM

The ornamental design for a lamp as shown and described.

DESCRIPTION

The patent or application file contains at least one drawing executed in color. Copies of this patent or patent application publication with color drawing(s) will be provided by the Office upon request and payment of the necessary fee.

1.1 : Front

1.2 : Back

1.3 : Left

1.4 : Top

1.5 : Bottom

1.6 : Perspective

1.7 : Perspective view in a folded position

1.8 : Another perspective view in a folded position

The right side view is omitted because it is a mirror image of the left side view; no claim is made for the color shown on the reproductions.

**1 Claim, 8 Drawing Sheets
(8 of 8 Drawing Sheet(s) Filed in Color)**
